UNITED STATES PATENT OFFICE.

THOMAS ALLSOP AND WALTER W. SIBSON, OF PHILADELPHIA, PENNSYLVANIA,
ASSIGNORS TO THE PHILADELPHIA DRYING MACHINERY COMPANY, OF PHILA-
DELPHIA, PENNSYLVANIA, A CORPORATION OF PENNSYLVANIA.

DYEING AND BLEACHING MACHINE.

1,245,139.

Specification of Letters Patent.

Patented Oct. 30, 1917.

Application filed August 11, 1916. Serial No. 114,327.

To all whom it may concern:

Be it known that we, THOMAS ALLSOP and WALTER W. SIBSON, of Philadelphia, in the county of Philadelphia and State of Pennsylvania, have invented certain new and useful Improvements in Dyeing and Bleaching Machines, whereof the following is a specification, reference being had to the accompanying drawings.

10 Our invention relates to dyeing and bleaching machines of the type in which steam is introduced into the dye liquor in the receptacle in which the goods to be dyed are immersed in said liquor. Heretofore it has been customary to introduce steam directly at or near the bottom of this receptacle from a steam pipe. The objection to this method is that if the steam is admitted too violently, it is apt to cause the liquor to boil over and scald the operator. Also the goods come directly in contact with the escaping steam which results in a tendency to strip off the color or cause streaks. It is also impossible to keep the entire body 25 of dye liquor at a uniform temperature since the liquor is more rapidly heated at the point where the steam jet escapes.

To overcome these objections, according to our invention, the perforated steam pipe is itself inclosed within a larger perforated pipe which although receiving the dye liquor within itself, and preferably acting as the outflow pipe of the system by which the dye liquor is circulated, prevents direct contact 35 of the goods with the steam pipe. Our invention also relates to the details of the mounting of the steam pipe and the arrangements for its ready disassembling which will be hereafter described.

40 In the accompanying drawings, Figure I, is a sectional view of the lower part of a dyeing and bleaching vat illustrating the application of our invention thereto.

Fig. II, is a cross sectional view on the line II, II, of Fig. 1.

45 Referring to the drawings, the dyeing receptacle 1, contains near its bottom, the large perforated guard pipe 2. This pipe extends preferably from one end of the receptacle to the other, being supported by its passage through the walls of the receptacle. At one end this pipe communicates with the pump 3, by which the dye liquor is circulated, being continuously withdrawn from

the receptacle by the pipe 2, and returned to it by the supply pipe not shown. The other end of pipe 2, is provided with a flange 4, to which is bolted a cap plate 5, centrally pierced for the reception of the steam pipe 6, which is perforated throughout its length as shown in the drawings. Pipe 6, may be closed at the end with the cap 7, which is provided as shown with an opening forming an end jet to assist the circulation. The support of the steam pipe with- 65 in the larger guard pipe 2, is such as to cause it to assume an axial position therein. This is preferably accomplished by means of the brackets 8, attached to the bottom of the steam pipe and reaching to the sides 70 of the pipe 2. The perforations of the guard pipe are larger than those of the steam pipe and are preferably arranged so as not to directly coincide therewith. A convenient way of arranging this is to place the perforations of the steam pipe in two side lines, as seen in Fig. II, and the perforations of the outer pipe in a single line along the bottom of said pipe.

80 In operation, the dye liquor is sucked into the pipe 2, by the pump 3, and thence returned to the receptacle by way of the supply pipe not shown. Steam is discharged from the perforations of the steam pipe and effects the heating of the liquor within the 85 pipe 2, being for the most part intermingled therewith before the liquor is returned to the dyeing receptacle. The pipe 2, enveloping the steam pipe effectually prevents the goods immersed within the dye liquor from com- 90 ing into injurious contact with the steam pipe or the steam escaping from it. Furthermore, our device causes a more even heating of the dye liquor than previously accomplished and prevents one portion of 95 said liquor in the receptacle from being raised to a higher temperature than others which objectionably affects the dyeing operation resulting in streaky goods.

100 When it is desired to remove the steam pipe for cleaning or other purposes, the unbolting of the cap plate 5, from the flanged head of the pipe 2, permits the steam pipe with its supporting brackets to be readily and freely withdrawn.

Having thus described our invention, we claim:

1. In combination with the dyeing recep-

2
tacle, a perforated pipe traversing the same, and a smaller perforated steam pipe received within said larger pipe and thereby kept from contact with the goods which are to be dyed within the dyeing receptacle.

5. 2. In a dyeing receptacle, the combination of a large perforated outlet pipe horizontally supported between the walls of said receptacle near the bottom thereof, and a smaller 10 perforated steam pipe supported axially within said larger pipe.

15. 3. In a dyeing machine, the combination of the dyeing receptacle, a large perforated pipe supported within the same, and between the walls thereof, an annular collar constituting the closure for one end of this pipe, a perforated steam pipe received within this collar and located along the axis of

said pipe, and bracket supports attached to the steam pipe and reaching to the walls of 20 the outer pipe.

4. In a dyeing receptacle, the combination of a perforated pipe, means by which the liquor is withdrawn from the receptacle and returned to it thereby causing the liquor to 25 pass through said perforated pipe, and a perforated steam pipe received within said perforated pipe.

In testimony whereof, we have hereunto signed our names at Philadelphia, Pennsylvania, this twenty-eighth day of July 1916.

THOMAS ALLSOP.

WALTER W. SIBSON.
